UNITED STATES PATENT OFFICE.

FREDERICK GOERTE, OF NEW YORK, N. Y.

DESIGN FOR THE ORNAMENTATION OF BOYS' JACKETS.

SPECIFICATION forming part of Design No. 16,006, dated March 31, 1885.

Application filed February 10, 1885. Term of patent 3½ years.

To all whom it may concern:

Be it known that I, FREDERICK GOERTE, of the city, county, and State of New York, have invented a new and original Design for the Ornamentation of Boys' Jackets, of which the following is a full, clear, and exact description, reference being had to the accompanying drawing, making part of this specification.

10 The design relates to an ornamentation for boys' jackets; and the design consists of a front or back for boys' jackets, having parallel braids and intermediate cords and so-called "crow-feet" of cords at the lower ends of the braids and cords.

15 The accompanying drawing represents a front view of an ornamentation for boys' jackets.

20 A in the drawing represents the front or back of a boy's jacket, and a a a number of parallel braids, of which one or more are arranged sidewise of each other.

Intermediately between the braids a a are arranged cords b b, parallel to the braids. The lower ends of the braids and cords are united, 25 by so-called "crow-feet" d d—that is to say, triangular pieces formed of cords. The braids and intermediate cords impart to the back and front the appearance of plaits and render the same very ornamental.

Having thus described my design, I claim as new and desire to secure by Letters Patent—

The design for the ornamentation of a boy's jacket, consisting of parallel braids, intermediate cords, and crow-feet of cords at the lower ends of the parallel braids and cords, as shown and described.

In testimony that I claim the foregoing as my invention I have signed it this 3d day of February, 1885.

FREDERICK GOERTE.
